Frank V. Ordman

ATTORNEY

UNITED STATES PATENT OFFICE.

RUDOLPH HERMAN WEBER, OF NEW YORK, N. Y.

JACQUARD MECHANISM FOR WEAVING MACHINES OR THE LIKE.

Application filed January 31, 1922. Serial No. 532,976.

To all whom it may concern:

Be it known that I, RUDOLPH HERMAN WEBER, a citizen of the United States of America, and a resident of New York, county of New York, and State of New York, have invented certain new and useful Improvements in Jacquard Mechanism for Weaving Machines or the like, of which the following is a specification.

10 The present invention relates to jacquard mechanism for weaving machines or the like and more particularly to the jacquard card. The ordinary jacquard card is generally made of a plurality of card-board strips arranged with their longitudinal edges parallel to one another and flexibly connected together by cord or the like to form an endless band, each strip being punched out according to a predetermined pattern to form one 20 or more holes, which are to register with corresponding bores in the jacquard cylinder, from which the endless band is suspended. The cylinder usually of polygonal shape, is rotatively supported in a vertically reciprocating frame and co-operates with a number of jacquard pins which control the operation of the weaving machine. As is well known, when the cylinder is moved upwardly towards the sets of jacquard pins, 30 the former actuates those of the pins which come into contact with the unperforated portions of a strip of the jacquard card, while the pins which are in range with the perforations of said strip are permitted to enter the bores or holes of the cylinder and remain inactive. Altho very little force, a force practically equal to the weight of a jacquard pin, is required to actuate the latter by the card, yet, owing to repeated application of 40 such force to the card the latter in a comparatively short time wears out. Apart from this, the card, being of easily destructible material, is liable to be damaged when in use. These are some of the principal objections to the ordinary jacquard cards.

Another more serious objection is the fact that for each pattern to be woven a separate jacquard card is required, so that, to afford a variety of patterns, a great number of cards must be kept in stock and new cards prepared for new patterns. The cards require a special stock room and owing to the cost of material and labor considerably add to the expense of manufacture.

55 The object of this invention is to obviate these drawbacks and to produce a universal

jacquard device, i. e., a band which can be used for any number of patterns, and also to make the band durable.

With these and other objects in view my invention consists in the construction of a device which is to take the place of the jacquard card and which is composed of a plurality of rows of individual members of rigid and durable material and flexibly connected together to an endless band, the individual members of each row being capable of being easily and quickly removed, so as to form free spaces for exposing particular holes in the jacquard cylinder, according to the pattern to be weaved. Thus a single band thus constructed can be used for any number of various patterns, by merely varying the location of free spaces through the removal of particular members from the band.

My invention also consists in means for holding the individual members of the band properly spaced relative to one another upon the removal of some of the members and also in means for securely holding the different rows in proper position relative to one another.

My invention also consists in means for guiding and feeding my new band over the jacquard cylinder and also in the novel construction, combination and arrangement of parts as will be hereinafter more fully described and set forth in the appended claims.

In the accompanying drawing in which similar reference characters denote corresponding parts, Fig. 1 is an elevation of a part of the jacquard mechanism showing my new jacquard band suspended from the jacquard cylinder; Fig. 2 is a longitudinal section on line 2—2 of Fig. 1; Fig. 3 is an enlarged view of a part of the jacquard band; Fig. 4 is a sectional view of a lock for securing the members on the rods; Fig. 5 is a section on line 5—5 of Fig. 4; Fig. 6 is a plan view of said lock; Fig. 7 is a face view of an individual member of the jacquard band and Fig. 8 is an end view thereof.

The jacquard mechanism, as is well known, comprises the jacquard cylinder *a* which usually is of square or polygonal cross section and which in each face is provided with two or more rows of cylindrical bores or holes *a'* arranged so that the bores or holes of one row are displaced relative to those of the other row. The cylinder *a* is suitably supported in a vertically reciprocating

frame *b* and through suitable mechanism receives an intermittent rotary motion. Co-operating with said cylinder are sets of jacquard pins *c* suspended above the latter and whereby the operation of the weaving machine is controlled in well known manner. Ordinarily an endless card composed of card-board strips specially perforated for a particular pattern is suspended from the cylinder *a* and is fed with the latter by teeth or prongs *d* projecting from each face thereof and meshing with perforations provided at the ends of each strip of the band so that during each partial rotation of the cylinder 15 a strip of the jacquard card is brought to bear on the upper face of the cylinder directed towards the jacquard pins to actuate the latter in well known manner.

According to my invention, the jacquard card is entirely dispensed with, but instead 20 I employ a device which is constructed as follows:—

Members 10 of rigid and durable material, preferably metal, are stamped out substantially in the shape best shown in Fig. 7, resembling in contour a globular flask or vase. At their end edges each member is of uniform width and cut out uniformly at 10' at opposite sides to form equally sized projections which are curved cylindrically to form eyelets or sockets 10². The cut out portion 10' are in length equal to the width of an eyelet so that it will accommodate an eyelet 10² of a member 10. The length of each member between its eyelets conforms with the width of a face of the cylinder *a*, while the belly portion 10³ of each member is so dimensioned that it will entirely cover a single bore *a'* of the cylinder *a*.

With their eyelets 10² these members are adapted to be strung in parallel rows on wires or rods 11 so that their bellies or broad portions 10³ alternate in position, i. e. one member will have its belly down, the adjacent members, up, the next following, again down and so forth, as shown in Figs. 1 and 7, to conform with the arrangement of the sets of bores *a'* in the cylinder. In this position the belly or the broad portion 10³ of each member will be accommodated in the cavities formed by the concave curves 10⁴ of the adjoining member and the eyelets 10² of the members of adjacent rows will be accommodated in the spaces formed by the cut out portions 10' of each member. The several rows of members 10 are strung on the rods 11 into an endless band. In addition to these members there is a member 12 at each end of a row, the inner edge 12' of which is curved to conform with the curvature of the opposite edge of the adjacent acting member and, therefore, to closely bear against said edge, while the outer edge 12² of each end member is straight. Each 65 end member is provided with a circular

opening or perforation 12³ to serve as a guide hole and to mesh with the prongs or teeth *d* of the cylinder *a*. These end members, too, at their ends are cut out as at 12⁴ at opposite sides similar to members 10 and 70 are formed with projections 12⁵ which are curved cylindrically to form eyelets or sockets, the cut out parts 12⁴ serving to accommodate the eyelets of the end members of the adjacent rows.

In order to secure the individual members and end members in assembled position on their rods 11, suitable locking means are provided. One form of such locking means, shown herein, consists of a sleeve 13 adapted to be removably mounted on the end of a rod 11 and formed with resilient fingers 13', the free ends of which are bent as 13² and adapted to engage an annular notch 11' made in the rod at a point where it will be 80 close to the outer edge of the end member. After the members are assembled on the rod 11 such locking sleeves are slipped over the ends of the rods with their tongues directed towards the end members and moved 85 until their bent ends snap into the corresponding notches of the rods.

As has been stated, in order to operate the jacquard pins according to predetermined patterns, corresponding holes and bores in the face of the polygonal cylinder which during the reciprocating movement of the latter is opposite the jacquard pins must be covered while others uncovered. Accordingly, those members of the jacquard device or band which register with the holes in the cylinder to be exposed or uncovered are removed from the chain or band so that the latter when set for a particular pattern has in each row one or more of the individual members missing, the number of such missing members and the location of the gap formed by the omission of a member depending upon the particular pattern. When one or more members in succession or at intervals are removed, care must be taken that the remaining members maintain their original position on the rods or be prevented from displacement thereon, since each member is designed for a particularly bore or hole of the jacquard cylinder. To accomplish this, I provide sleeves 14 adapted to be removably mounted on the rods 11 and of a length equal to that of the cut out portion 10' of an individual member. When a member is removed from the rods 11 it is replaced by a sleeve 14 which will exactly fill the vacant space on the rod 11 and serve thus as a spacer. In case of the removal of two or more adjacent members, a corresponding number of spacers will be mounted on the rods to fill the space of the eyelets of the removed members.

The band is suspended from the cylinder to hang down freely like the ordinary

jacquard card, the prongs *d* of the polygonal cylinder meshing with the holes 12³ in the end members 12 and guiding and feeding the band as the cylinder rotates and its effect on the jacquard pins will be the same as that of the ordinary card.

For each new pattern the band will be rearranged, i. e., some of the members 10 removed to create spaces to expose particular bores in the cylinder. It thus is clear 10 that my device can be effectively used for various patterns.

What I claim and desire to secure by Letters Patent is:—

- 15 1. In a jacquard mechanism for weaving machines, or the like, the combination with the jacquard cylinder having holes or bores, of an adjustable endless jacquard band composed of flexibly connected rows of removable individual solid members, each to fit over and when removed to expose a single hole in said cylinder.
- 20 2. In a jacquard mechanism for weaving machines or the like, the combination with the jacquard cylinder having sets of holes and projections, of an adjustable endless jacquard band composed of a plurality of flexibly connected rows of removable individual solid members each to fit over and when removed to expose a single hole in said cylinder, and removable end members having perforations adapted to mesh with said projection to guide and feed said band around said cylinder.
- 25 3. In a jacquard mechanism for weaving machines or the like, the combination with a polygonal jacquard cylinder having sets of bores in each face, of an endless adjustable jacquard band composed of a plurality of rows of individual rigid and solid members, means for removably connecting said individual members to each other and for flexibly connecting the said rows to one another, the said members being all of uniform shape and in length equal to the width of a face of said polygonal cylinder, and in width so admeasured as to fit over and when removed to expose a single hole of said cylinder.
- 40 4. In a jacquard mechanism for weaving machines or the like, the combination with the jacquard cylinder having sets of bores, of an endless adjustable jacquard band,

composed of flexibly connected rows of removable individual solid members, each to fit over and when removed to uncover a single hole in the cylinder, and means for locking said members in assembled position.

5. In a jacquard mechanism for weaving machines or the like, the combination with the jacquard cylinder having a plurality of holes, of an endless adjustable jacquard band composed of flexibly connected rows of removable individual solid members each to fit over and when removed to expose a single hole in said cylinder, and means for holding the individual members in their position after the removal of any one of said members.

6. An endless jacquard band composed of a plurality of rows of individual solid acting members of rigid material and perforated end members, each member being formed at its ends with tubular eyelets, rods on which said members are strung with said sockets and whereby the several rows are connected together, means for locking the said members in assembled position and spacers adapted to be removably mounted on said rods to fill the spaces of the eyelets of the removed members and to hold the remaining members in their respective positions.

7. An endless jacquard band composed of individual acting members, each member having a broad portion adapted to fit over a single hole of a perforated jacquard cylinder, eyelets at opposite sides of its end edges and a cut out portion adjacent each eyelet.

8. In combination with a polygonal jacquard cylinder having on each face displaced rows of bores, an endless jacquard band composed of rows of individual acting members each shaped to fit over a single bore of one of said rows and removably strung together so that the members of each row will alternately cover the bores of the different rows, and end members for guiding and feeding said band around said cylinder.

Signed at New York, N. Y., this 28th day of January, 1922.
